PISTON RING TOOL

Stephen A. Dionne, Green Bay, Wis.

Application April 21, 1945, Serial No. 589,531

3 Claims. (Cl. 29—222)

1

This invention relates to improvements in a tool for handling piston rings. My improved tool is serviceable both for the removal and mounting of piston rings.

It is a primary object of the invention to provide a novel and simplified tool which may be used with facility, while leaving both of the operator's hands available for manipulation of the ring in substantially a normal manner.

My improved tool comprises a pair of finger or thumb stalls hingedly connected and provided with ring engaging prongs. With the thumb of each hand or one finger of each hand engaged in their respective stalls, the prongs may be engaged with the ends of a split ring to spread such ends, and all the remaining digits of the operator's hands may be used to support and guide the ring, the operation being so natural that the presence or absence of the tool makes little difference in the way the operator uses his hands. In effect, the digits engaged in the stalls constitute extension levers for the manipulation of the ring tool. Thus neither hand is fully occupied as is the case in manipulating a pair of pliers or the like, and the manipulation of the ring is accomplished naturally and with no requirement for special skill or training.

It is a further object of the invention to provide a simple and less expensive tool than any heretofore available.

Other objects will be apparent to those skilled in the art upon analysis of the following disclosure of the invention.

In the drawings:

Fig. 1 is a view taken in section horizontally through a piston and illustrating, partially in plan and partially in section, a tool embodying the present invention as such tool appears in use.

Fig. 2 shows in plan the tool of Fig. 1 as it appears when the ends of the split ring have been more widely separated, the ring being fragmentarily illustrated.

Fig. 3 is a detail view of the tool in perspective as viewed from its inner side.

The piston 4 has the usual ring groove at 5 in which the split piston ring 6 is disposed.

My improved tool comprises a pair of metal finger stalls 7, 8, having hinge ears 9 and a pintle 10 connecting their disk-like ends 11, 12, at a point near their respective curved outer walls 13, 14.

The precise shape of the finger stalls is immaterial. It is immaterial whether they are skeletalized or are closed as shown. The end walls 11, 12, are optional. The stalls are preferably

short enough to terminate at about the first joint of the operator's thumb or forefinger and are preferably shorter on the inside than on the outside, as clearly appears from each of the several views.

5 The stalls are provided at their inner side portions, remote from the hinge pintle 10, with laterally projecting prongs 15, 16. These prongs are preferably not materially greater in length than the cross section of the average piston ring 6 and 10 so located as to spread the split ends of the ring when the stalls are hingedly manipulated. Either the operator's thumbs or his forefingers 15 may be inserted in the stalls to operate them. In either case, the rest of the operator's hands may 20 extend in a natural manner about the ring 6 which is to be manipulated. This is important because it enables the operator to use for the support and guidance of the ring those digits of both hands which are not engaged in the manipulation 25 of the tool. If the ring were supported solely at its split ends, it would tend to sag at its closed side and, therefore, to escape from accurate registration with the groove, or to catch on other rings. Since the operator's hands are freely 30 available for supporting and guiding the ring at both sides of the piston, the ring may with facility be opened or closed and manipulated to and from position. The spreading and reclosing of the ring is accomplished by simply flexing the joints of the digits which are engaged in the respective stalls 35 7, 8.

I claim:

1. A piston ring tool comprising a pair of stalls each adapted to receive a digit of an operator's hand, each stall comprising an open ended socket of substantial depth to receive a major portion of a joint of said digit, a hinge connecting said sockets adjacent their side and end so that the open ends of said sockets will be oppositely directed 35 when said sockets are moved upon said hinge to a position of substantial alignment, each of said sockets having a closed end wall at its end adjacent the hinge, and a prong extending laterally away from the hinge at the side of each socket opposite said hinge.

2. A piston ring tool comprising a pair of encircling elements each of substantial extent to receive and encircle a length of the digit of an operator's hand and providing opposed ends, 40 means adjacent an end and side of each element to directly hinge said elements together so that they may be pivoted into axial alignment for reception of an operator's digits at the opposite ends as said digits move toward each other, and prongs 45 extending generally radially outwardly from a

3

point adjacent the wall of each element diametrically opposite to said hinge location and at said hinged end.

3. A piston ring tool comprising two sockets, each socket being open at least at one end and being of substantial length to receive a digit of an operator's hand, hinge means directly connecting each of said sockets at the end opposite said one end, a ring engaging prong carried by each socket at said opposite end and each prong extending at approximately right angles to the length of its socket.

STEPHEN A. DIONNE.
